US0D1050071S

(12) **United States Design Patent** (10) Patent No.: **US D1,050,071 S**
(45) Date of Patent: ** Nov. 5, 2024

(54) **HEADPHONES**

(71) Applicant: **Audio-Technica Corporation**, Tokyo (JP)

(72) Inventors: **Kohei Yoshida**, Tokyo (JP); **Masahiko Takahashi**, Tokyo (JP); **Tatsuya Kawai**, Aichi (JP)

(73) Assignee: **Audio-Technica Corporation**, Tokyo (JP)

(**) Term: **15 Years**

(21) Appl. No.: **29/872,830**

(22) Filed: **Mar. 20, 2023**

(30) **Foreign Application Priority Data**

Sep. 30, 2022 (JP) ..... 2022-021134 D

(51) **LOC (14) Cl.** **14-01**

(52) **U.S. Cl.**

USPC **D14/205**

(58) **Field of Classification Search**

USPC D14/205, 223; D24/174; 128/864-866; 381/380-381

Primary Examiner — Paula Allen Greene

(57) **CLAIM**

The ornamental design for headphones, as shown and described.

DESCRIPTION

FIG. 1 is a top, front, right side perspective view of headphones, showing the new design;
FIG. 2 is a top plan view thereof;
FIG. 3 is a bottom plan view thereof;
FIG. 4 is a rear view thereof;
FIG. 5 is a front view thereof;
FIG. 6 is a left side view thereof; and,
FIG. 7 is a right side view thereof.

Evenly broken lines depict portions of the headphones which form no part of the claimed design.

1 Claim, 6 Drawing Sheets
